UNITED STATES PATENT OFFICE.

FRITZ LOCHER, OF ZÜRICH, SWITZERLAND, ASSIGNOR TO THE FIRM OF
LOCHER & CIE., OF ZÜRICH, SWITZERLAND.

MOLD FOR CONSTRUCTING HOLLOW CONCRETE COLUMNS.

No. 840,637.

Specification of Letters Patent.

Patented Jan. 8, 1907.

Application filed November 10, 1906. Serial No. 342,921.

To all whom it may concern:

Be it known that I, FRITZ LOCHER, a citizen of the Republic of Switzerland, residing at Zürich, Switzerland, have invented certain new and useful Improvements in Molds for Constructing Hollow Concrete Columns; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The subject of my invention is an apparatus for making hollow beton or concrete pillars or columns.

The new apparatus consists of a mold composed of a plurality of superposed detachably-connected sections each comprising an outer shell and a core inclosed by the same.

One form of construction of the invention is illustrated in the accompanying drawings, in which—

Figure 1 is a side elevation; Fig. 2, a vertical section through the lower portion of Fig. 1 drawn to a larger scale; Fig. 3, a cross-section on the line A B of Fig. 2; Fig. 4, a cross-section through a concrete column constructed by means of the apparatus, and Fig. 5 a sectional view illustrating the structure employed for supporting the mold when making such a concrete column.

The apparatus consists of a mold composed of a number of superimposed sections *a*, each comprising a shell *b*, having a slightly-conical taper in upward direction, and a similarly-tapering core *c*, inclosed by the shell. The cores are so located relatively to the shells that between the former and the latter an annular space remains extending throughout the entire height of the mold. From the rear side of the shell-sections there project arms *d*, by means of which the sections can be detachably secured to vertical bars *e*. These bars are fixed to a framework or scaffold *T*, having platforms or stages *E*, to which the workmen can ascend by steps or ladders *L*. Each shell-section *b* is split into two halves *b'* *b''*, of which the former turns on hinges *f*.

g represents metal bows pivoted to lugs projecting from the part *b''*. They are furnished with press-screws and take over the

lugs *h* of the part *b'* in the manner of a hasp, whereby the two halves *b'* *b''* can be locked together, as shown in Fig. 3.

At the bottom of the cores spiders or transverse members *k* are provided, in which are suspended bolts *i*, the heads *i'* of which are of elongated rectangular shape. The boss of the spiders is provided with elongated slots *k* to receive the bolt, and to prevent rotation of the latter the neck of the bolt-shank, which lies within the boss, is rectangular. The bolts pass farther through the elongated rectangular slots *l* in the spiders *s* at the tops of the cores. The tails of the bolts *i* terminate in elongated rectangular pieces located transversely to the heads *i'*. *m* represents dowel-pins entering recesses in the ends of each two abutting cores. *n* is a hollow flared foot upon which the bottom shell-section rests. This foot supports a ring *o*, which closes the bottom of the annular space between shells and cores—that is to say, is destined to support the column to be erected. In the hollow foot is a vertically-adjustable support *p*, on which the bottom core-section stands.

To construct a column, I proceed in the following manner: On the foot *n* all the shell-sections are erected, and on the support *p* to start with only the lowest core-section, whereupon the annular space between the shell and the core of this lowest column-section is filled out with concrete. On the bottom core-section the next higher one is now set and the space between shell and core then filled out with concrete, as before, and so on, working from platform to platform until all the sections have been erected one upon the other and the annular spaces between shells and cores filled up with concrete. During this procedure the core of the mold must be turned from time to time by rotation of the support, the motion of the latter being transmitted to the core above by means of the dowel-pins *m*. The purpose of this rotation of the core at intervals is to prevent the concrete mass from adhering to the wall of the core. When the concrete in the mold has hardened, the core has to be withdrawn. For this purpose the top core-section is suspended from the structure *T* and the support lowered, whereupon all the core-sections (except the top one) will descend also. The descent of the support is continued until the spiders *s* of the cores strike the tailpieces *i''* of the bolts *i*.

lying transversely to the slots l , so that the whole of the cores and bolts hang one from the other. This concatenation of cores and bolts is then further lowered until the core of 5 the bottom column-section entirely leaves the shell, whereupon this core is detached from the one above it. This is done by the bottom core being rotated relatively to the next higher one until the tailpiece i^2 of the 10 bolt i passes through the slot l of the bottom core. The concatenation of cores is then lowered in any suitable manner until the originally penultimate core (now the ultimate or 15 lowest one) entirely leaves the mold, whereupon this core is detached, and so on until all the cores are removed from the mold. The parts b' of the shells are then flapped back on their hinges f , so that the hollow column formed by the concrete which has been filled 20 into the annular space between cores and shells can be removed laterally. The cross-section of such a column is seen in Fig. 4. This column is reinforced by means of wires q , running longitudinally of the column, and 25 wires r , running transversely to the same.

Having now particularly described and ascertained the nature of the said invention and in what manner the same is to be performed, I declare that what I claim is—

30 1. In apparatus for making hollow concrete columns, in combination, a tubular mold, consisting of a plurality of superposed sections; a hollow core consisting of a plural-

ity of superposed sections, located within the said mold; and detachable members connecting the individual core-sections together, 35 substantially as described.

2. In apparatus for making hollow concrete columns, in combination, a tubular mold, consisting of a plurality of superposed sections; a hollow core, consisting of a plurality of hollow sections, located within the said mold; transverse members having elongated slots, located at the ends of the cores; and bolts having elongated heads and tail-pieces passing through the slots of each two adjacent transverse members, the distance between the head and tail of the bolts being greater than the distance between the top of one transverse member and the bottom of the 40 adjacent one; substantially as described.

3. In apparatus for making hollow concrete columns, in combination, a tubular mold, consisting of a plurality of superposed sections; a hollow core, consisting of a plurality of superposed sections, located within the mold; and dowel-pins on the end of each core entering recesses in the adjacent end of the next core; substantially as described.

In testimony that I claim the foregoing as 6c my invention I have signed my name in presence of two subscribing witnesses.

FRITZ LOCHER.
